DESIGN FOR A HANDBAG OR THE LIKE

Virginia Blake, New York, N. Y.

Application August 21, 1941, Serial No. 102,981

Term of patent 3½ years

To all whom it may concern:

Be it known that I, Virginia Blake, a citizen of the United States and residing at New York city, in the county of New York and State of New York, have invented a new, original, and ornamental Design for a Handbag or the like, of which the following is a specification, reference being had to the accompanying drawing, forming part thereof, and in which

Fig. 1 is a side perspective view of a handbag or the like showing my new design with the flaps in raised position;

Fig. 2 is a top plan view of Fig. 1;

Fig. 3 is a side perspective view thereof with the flaps in lowered position;

Fig. 4 is a reduced side perspective view of the bag shown in Figs. 1, 2, and 3, with the handles beneath one flap drawn to an elevated position causing the two flaps to lie only on one side of the bag; and

Fig. 5 is a side elevational view with the handles drawn from the top to an elevated position resulting in a gathered effect.

I claim:

The ornamental design for a handbag or the like, substantially as shown.

VIRGINIA BLAKE.
